UNITED STATES PATENT OFFICE.

WILHELM BAIER, OF MUNICH-STOCKDORF, GERMANY.

GARMENT HANGER.

Application filed October 11, 1926. Serial No. 140,942.

This invention relates to a collapsible garment hanger, composed of two short U-shaped sheet metal bodies connected the one to the other by a hinge, an elastic fork being inserted in each body so that it can be shifted in longitudinal direction between two stops, one of said forks having at the outer end the hook and the other one the button hole for the garment to be suspended, i. e. the trousers. According to the invention a safety device is provided designed to ensure the accurate joining of the edges of the U-arms of the two bodies when the garment hanger is being unfolded to adapt the position of use, and further a locking device for securely holding the two bodies in the position of use, and means for stiffening the two arms of the U-shaped fork of each body at the hinge point, the suspension hook being constructed to serve as hinge pin.

An embodiment of the invention is shown, by way of example, in the accompanying drawings in which:—

Fig. 1 shows in a central longitudinal section the garment hanger in the position of use.

Fig. 2 is a cross section on line I—I of Fig. 1, on larger scale.

Fig. 3 is a plan view of Fig. 1 viewed from below.

Fig. 4 shows in side elevation the garment hanger collapsed.

Fig. 5 is a similar view as Fig. 4 turned 90°.

The two elements or bodies 1 and 2 of the garment hanger are of substantially U-shaped cross section, the edges of the arms being bent inward. The two elements 1, 2 are connected the one to the other by a hinge 3. The U-arms of the two elements are larger at the inner ends than at the outer ends. In each of the hollow bodies 1 and 2 an elastic fork 4, 5 is inserted, the arms of which have the tendency to spread away the one from the other so that they press onto the side arms of the hollow bodies. Each fork is shiftable in the corresponding body between two stops 6 and 7, in opposition to the fixation produced by the elastic pressure of the fork arm upon the arm of the hollow bodies. Owing to this shiftable arrangement of the forks 4, 5 the garment hanger can be adjusted to the size of any garment, i. e. to the shoulder-width of a waist coat. The inner stop 6 for the fork 4 or 5 consists of a piece of sheet metal

of angular cross section fixed on the inner surface of the back of the hollow body, the outer stop 7 being formed by two flaps bent inward from the edge of each arm of the corresponding body.

The arms of each fork 4 and 5 are bent at the inner end at 8 and 9 (Fig. 5) at right angles inward direction and these inwardly bent ends abut in the two extreme positions of the fork against the stops 6 or 7 respectively. To the outer web of fork 5 a lug 10 is attached, a hook 11 being suspended to the outer web of the other fork 4. A pair of trousers can be suspended in the well known manner into the lug 10 and hook 11.

The lug 10 and the hook 11 are oscillatably mounted on the webs of the forks 4, 5.

The arms of the U-shaped cross section of the elements 1 and 2 are cut at the hinge point so that, if the two elements or bodies 1, 2 join in the position of use, the edges 12 and 13 of the joining elements form a convenient angle, as shown in Fig. 1. In order that the edges of the two elements come accurately into contact the one with the other the element 2 has on the contact edge of each arm a flap 14 which is fixed in close proximity to the hinge 3 by a rivet 15 on the corresponding arm of the U-shaped cross section and partly overlaps the contact edge 12 and projects over the edge of the arm of the U-shaped cross section. This projecting portion of flap 14 forms a guide for the contact edge of the arm of the opposite element.

At the inner end of each arm of the element 2 of U-shaped cross section an inwardly bent nose 16 is arranged designed to come into engagement with a notch 18 in the corresponding flap 14 as shown in Figs. 3 and 4. On the end of each arm of the element 1 a similar nose 17 is arranged, said noses 17 engaging with the notches 18 of the flaps 14 when the two elements of the garment hanger are in the position of use, the flaps yielding elastically in outward directions. The two elements of the garment hanger are thus secured in the position of use, and to release the same a pressure has to be exerted upon the projecting portions of the flap 14.

In order to prevent yielding of the arms of each element 1, 2 of U-shaped cross section at the inner ends in outward direction inwardly bent opposite flaps 19, 20 of said arms are connected the one to the other, as closely as possible to the contact edges 12, 13 by a clasp 21. The two clasps 21 may

be used for suspending on the same for instance a trouser's stretcher.

The hinge pin 22 is formed by the end of the suspension hook 23 which is bent at 5 right angles.

The suspension hook 23 can consequently be turned to lay flat on one side wall of the hanger, the other side wall and the whole back of the garment hanger being thus 10 available for the garments so that, for instance the stiff collar of a uniform would stand above the hinge without abutting against the suspension hook.

To collapse the garment hanger the two 15 forks 4, 5 are to be pushed in up to the stops 6, the hook 23 is to be turned down and the locking noses 17 are released by the pressure of a finger exerted upon the projecting ends of the flaps 14, whereupon the 20 two elements 1 and 2 are turned upward so that their backs come into contact as shown in Fig. 4. The hook 11 is partly situated between the arms of fork 4 and the lug 10 is laid onto its fork 5, as shown in Fig. 5.

25 Owing to the clasps 21 and to the guide flaps 14 the two elements of the garment hanger can be made from very thin sheet metal so that the garment hanger is of light weight. In the collapsed position the hanger occupies little space so that it can be easily packed.

I claim:—

1. A collapsible garment hanger comprising in combination, two hollow elements of 35 sheet metal of U-shaped cross section the arms of the U-shaped cross section getting narrower towards the outer end the inner end of each element being cut so that the two elements join at a suitable angle, a hinge

connecting the two elements at the inner 40 ends, a fork shiftable in each hollow element and having elastic arms, two stops in each hollow element for limiting the shifting of said forks in both directions, an elastic flap at each side of each element at the inner end 45 of said element for guiding the side arms of the opposite element at the unfolding of the hanger and having a notch, and noses at the inner ends of the arms of each element and designed to engage with the notch 50 of the opposite flap to secure the two elements in the position of use.

2. A collapsible garment hanger comprising in combination, two hollow elements of sheet metal of U-shaped cross section the 55 arms of the U-shaped cross section getting narrower towards the outer end the inner end of each element being cut so that the two elements join at a suitable angle, a hinge connecting the two elements at the inner ends, 60 a fork shiftable in each hollow element and having elastic arms, two stops in each hollow element for limiting the shifting of said forks in both directions, an elastic flap at each side of each element at the inner end 65 of said element for guiding the side arms of the opposite element at the unfolding of the hanger and having a notch, noses at the inner ends of the arms of each element and designed to engage with the notch of 70 the opposite flap to secure the two elements in the position of use, and a clasp in the inner end of each element holding together the opposite side arms of each hollow element. 75

In testimony whereof I affix my signature.

WILHELM BAIER.
